UMBRELLA RIB TIP

Richard Wallace Carlisle, Elmsford, N. Y.

Application September 24, 1936, Serial No. 102,289

13 Claims. (Cl. 135—36)

This invention relates to blunt tips for the ribs of umbrellas the term umbrella being taken to include parasols.

At present many tips are used, differing principally in the methods by which the fabric is attached to the tip and the tip to the rib. All of these present tips, however, are pointed at the ends and so present a hazard to persons walking or standing close to the open umbrella or parasol. It is the principal object of my invention to remove this hazard by providing a blunt tip, while at the same time performing all the functions which the present day tips perform.

It is another object to prolong the life of the fabric by reducing fabric stresses at the rib tips.

It is another object of this invention to provide a tip which will be so decorative as to enhance the appearance of the entire umbrella.

It is another object to effect economies by reducing the number of ribs required.

According to my invention, I provide a rib end member widened along the periphery of the umbrella but flattened and disposed below the fabric, and a shallow decorative protrusion on the outside of the fabric.

Various methods of constructing said rib end member and said decorative member, separately or in one piece, are shown in the accompanying drawing, in which

Fig. 1 is a plan view of a rib and tip assembly wherein the tip is formed of a plastic member arranged to receive the rib and retain the fabric.

Fig. 2 is a sectional view through the line 2—2 in Fig. 5 shown in front elevation.

Fig. 3 is a sectional view along the line 3—3 of Fig. 5 shown in front elevation.

Fig. 4 is a front elevation of a decorative insert which fits into the frame shown in Figs. 7 and 8.

Fig. 5 is an exploded perspective view of a rib end assembly comprised of a widened rib end member made of pressed metal, a decorative insert and an end shell.

Fig. 6 is a plan view of the assembly shown in Fig. 5.

Fig. 7 is a plan view of the end piece shown in Figs. 5 and 6, before assembly.

Fig. 8 is a front elevation of the shell of Fig. 7.

Fig. 9 is an exploded view in perspective of a rib tip assembly showing a decorative tip formed of plastic material and mounted on a widened rib end member by means of a wire insert.

Fig. 10 is an exploded view of a method of retaining the fabric on an elongated rib tip by means of buttons.

A single molded or cast member 7 designed to perform the functions of the elongated support and of the decorative member is shown in Figs. 1, 2 and 3. The member 7 has a hole 8 therein into which is inserted the rib R, which is affixed therein by means of the pins 9 closely fitting beside the corrugations 10 in the rib R. The fabric F is placed in the slot 11 and is held by the seam of the fabric and by pins in the enlarged end portions 12 of the slot 11.

A simplified form of mounting the strip 16 of decorative material is shown in the exploded view of Fig. 5, in which the shell 17 shown in Figs. 7 and 8 is used as a frame for retaining the strip 16, while the tongues 18 and 18' are bent over inside the holes 19 to simultaneously affix the shell 17 to the supporting member 15 and to anchor the fabric F. Another method of decorating the rib tip is to mount jewels in the shell as indicated in Fig. 4.

The supporting member 15 may be either pressed from sheet metal, as indicated in the plan view of Fig. 6, or cast or molded in a solid piece. If constructed from sheet metal it may be spot welded, soldered or brazed to the rib R. If cast or molded, it may either be cast or molded integrally with the rib R or affixed in the manner shown in Fig. 1.

One method of attaching a molded or cast decorative piece is shown in Fig. 9, in which the elongated metallic member 24 is molded or cast into the decorative piece 23, or affixed to the under surface thereof by means such as soldering or brazing. This member 24 is inserted in holes 25 during assembly and used to anchor the fabric and affix the member 23 in place on the rib tip 22. Alternatively, the member 24 may be a screw.

Another method of attaching the fabric is to use buttons 28 as shown in Fig. 10. Recesses 29 are provided in the rib tip 30 for the buttons which should preferably be of the form having no holes on the outside but an eye 32 on the inside. The buttons 28 may alternatively be sewn in place or attached by staples to the holes 31 and 31'. Alternatively, the fabric may be sewed in place without the use of buttons.

No restriction is placed on the position of holes 29 and 31, as to whether they should be on the front, top, or sides of member 30.

In all of these designs, the life of the fabric is considerably increased over standard designs.

because the large area over which the fabric is attached at each rib tip results in lowered fabric stresses.

In the design of rib tips according to my invention, no restrictions are placed upon the relative thickness and width of each tip, or upon the angles at which said tips may be set, in order to allow the widest latitude for decorative design. Neither is any restriction placed upon the thickness of the member which is retained affixed over the fabric, as 7' in Fig. 3 and 17 in Fig. 6.

It may be seen that an umbrella may be constructed with a reduced number of ribs when each rib is equipped with a broadened tip, which will effect a considerable economy in manufacture.

Other methods of constructing a widened tip and decorating it may be used, but the combination of safety and decorative features is claimed as follows:

1. A blunt tip for an umbrella rib comprised of a member much broader than said rib, in combination with a covering, said broad member being disposed along said rib extending inwardly from the outer end thereof and substantially in a plane juxtaposed to said covering, and said member having along the outer edge thereof means for affixing said covering thereto.

2. The combination with an umbrella having a covering, of a rib having a multi-sided tip much broader across the end than said rib and extending outwardly and downwardly therefrom, the outer side of said tip being parallel to and near the edge of said covering.

3. A blunt tip for an umbrella rib comprised of a broad body of molded material, in combination with a covering, said molded body being disposed along said rib extending inwardly from the outer end thereof and in a plane below and juxtaposed to the under side of said covering, and means for affixing said covering to said broad body along the outer edge thereof.

4. The combination with an umbrella rib of a tip having a widened end with a groove along the outer edge thereof, a covering, and means for retaining said covering in said groove.

5. The combination with an umbrella rib of a tip having a widened end with a groove along the outer edge thereof, a covering, and means for retaining said covering in said groove at each end thereof.

6. An umbrella tip having a broadened tip, in combination with a covering conforming to the outer surface thereof and a shell disposed over said covering on the end of said tip.

7. The combination with an umbrella rib of a widened tip, a covering and means for attaching said covering to said tip comprised of a shell partially enclosing the outermost edge of said widened tip.

8. In combination, a blunt tip for an umbrella rib comprised of a broad solid body, and means for affixing said body to said rib comprised of

undulations formed along said rib near the end thereof, an elongated hole in said body, and means for retaining said rib in said hole utilizing a clamping action upon said undulations.

9. A blunt tip for an umbrella rib comprised of a three-cornered member, means for affixing said member rigidly to said rib at one corner, in combination with a covering and means for affixing said covering onto said member along the side of said member opposite to the corner at which said rib is affixed, comprised of a slot in said member substantially parallel to the edge thereof into which the edge of said covering is inserted.

10. A blunt tip for an umbrella rib comprised of a three-cornered member, means for affixing said member rigidly to said rib at one corner, in combination with a covering and means for affixing said covering onto said member along the side of said member opposite to the corner at which said rib is affixed, comprised of a slot in said member substantially parallel to the edge thereof into which the edge of said covering is inserted, and means in association with said slot for retaining said covering within said slot.

11. A blunt tip for an umbrella rib comprised of a three-cornered member, means for affixing said member rigidly to said rib at one corner, in combination with a covering and means for affixing said covering onto said member along the side of said member opposite to the corner at which said rib is affixed, comprised of a slot in said member substantially parallel to the edge thereof into which the edge of said covering is inserted, and means in association with said slot for retaining said covering within said slot, comprised of means for wedging said covering into said slot.

12. A blunt tip for an umbrella rib comprised of a three-cornered member, means for affixing said member rigidly to said rib at one corner, in combination with a covering and means for affixing said covering onto said member along the side of said member opposite to the corner at which said rib is affixed, comprised of a slot in said member substantially parallel to the edge thereof into which the edge of said covering is inserted, and means in association with said slot for retaining said covering within said slot, comprised of means for wedging said covering into said slot at each end thereof.

13. A blunt tip for an umbrella rib comprised of a broad solid body disposed substantially in a plane below the umbrella covering and extending along the periphery thereof, means for attaching said covering to said body, and means for attaching said body to said rib comprised of undulations formed along said rib near the end thereof, an elongated hole in said body disposed radially with respect to the outer edge thereof, and means for retaining said rib in said hole utilizing the undulatory nature of the surface of said rib.
